Primary Examiner — Clare E Heflin*(74) Attorney, Agent, or Firm* — Notaro, Michalos & Zaccaria P.C.(57) **CLAIM**

The ornamental design for a rock disk light, as shown and described.

DESCRIPTION

FIG. 1 is a top left perspective view of a rock disk light showing our design therefor;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The dotted lines indicate boundaries with the claimed subject matter being outside these boundaries.

1 Claim, 5 Drawing Sheets
